John Onders Jr.

Inventor:

George P. McIntyre,
By Dymforth, Dymforth^{by} See,
1775.

UNITED STATES PATENT OFFICE.

GEORGE P. MCINTYRE, OF CHICAGO, ILLINOIS.

MAILING-TUBE.

SPECIFICATION forming part of Letters Patent No. 656,825, dated August 28, 1900.

Application filed January 29, 1900. Serial No. 3,144. (No model.)

To all whom it may concern:

Be it known that I, GEORGE P. MCINTYRE, a citizen of the United States, residing at Chicago, in the county of Cook and State of Illinois, have invented a new and useful Improvement in Mailing-Tubes, of which the following is a specification.

My invention relates to an improvement in the class of tubular receptacles for containing such articles to be transmitted through the mail as are subject to inspection, to enable which the tubes are required to permit ready access to their contents and ready reclosure of the package after the inspection.

More particularly my present invention relates to an improvement upon the construction of mailing-tubes for which Letters Patent of the United States No. 524,860 were granted to me August 21, 1894.

The mailing-tube of my aforesaid patent, while adapted to afford a receptacle for mailable articles generally of the character suitable for transmission in tubes, is not especially designed for holding liquids or liquids in frangible receptacles for transmission by mail.

My object now is to provide a construction of mailing-tube especially adapted for holding liquids for mailing and which, while possessing the attributes hereinbefore referred to of permitting ready access to its contents and ready reclosure of the package after inspection of its contents, shall, besides being waterproof and capable of close sealing against leakage, be provided with a cover and fastening means therefor so constructed as to cause the cover to brace the tube in an outward direction against crushing strain exerted against it and to cause the cover-fastening means on the tube to coöperate with the cover to resist transverse elongation of the tube at its covered mouth portion, which would obviously then open it and afford a leak in the receptacle even though the cover remain in place under the strain referred to.

In the accompanying drawings, Figure 1 is a view in vertical sectional elevation of my improved mailing-tube, showing all its parts but the cover and washer; Fig. 2, a similar but broken view of the same showing the cover fastened in place; Fig. 3, a cross-sec-

tional view of the cover; Fig. 4, a similar view of a washer detail; Fig. 5, a similar view of a modified form of the washer, and Fig. 6 a perspective view of a clip detail.

55

A is the tube, comprising two tubular sections A' and A'', fastened together, as by cementing one within the other, the outer one being the longer of the two to afford the internal end shoulders r and r', which form 60 seats, respectively, for the head p and cover B.

While I do not limit my improvement to any particular material out of which to form the tube, that selected must of course be suitable for the purpose of the tube, and because 65 it should for economical reasons be as light as is consistent with the requirements of strength and durability I prefer to select as the material ordinary pasteboard.

In forming the tubular portion of my improved device, which may be done by inserting the one tubular section into the other with the glue or other cement applied preparatory, say, to the outer surface of the inner one, so as to unite them in the relative positions to which they are adjusted to form the end shoulders, I interpose between the tube-sections adjacent to the shoulder r flexible metal clips C, preferably four in number and equidistant apart. In order to afford a hold upon each clip between the tube-sections, it should be formed widest toward its base and contain an opening o, through which to admit the cement provided between the tube-sections, so that when the cement becomes 85 hard it affords a species of key in the clip-opening.

The end of the tube A at the shoulder r' is permanently closed by the head p, which is best formed of wood saturated with or dipped 90 in shellac and which fits against and is cemented to the shoulder r', the head being, by preference, further secured in position by means of a covering m of cloth cemented about the inner tube-section A', adjacent to the 95 shoulder r', and to hide this cloth covering I prefer to cement against its outer surface a thin disk of paper or pasteboard l.

When the tube A is formed of pasteboard, to render it waterproof I coat it internally 100 with paraffin k or some other suitable waterproofing material.

The cover B should be formed of metal in the generally concavo-convex shape illustrated, and about its edge it is provided with an upwardly-flaring flange *i*, which should, by preference, be slightly curved in cross-section, as represented. Against the shoulder *r* I apply a washer *h*, which is best formed of rubber, and it may be beveled, as shown at *x*, from its upper outer edge to its lower inner edge to afford a close-fitting seat for the cover, conforming more or less accurately to the cross-sectional approximate V shape of the flanged edge of the cover. The rubber washer *h* may also be tubular and in cross-section, as shown in Fig. 5. With the cover in its seat the clips C are bent over its flange *i* and secure it in place in a manner to permit it to be readily removed on bending back the clips.

As will be seen, any pressure or weight that is brought to bear against the side of my improved tube A, with the cover fastened in place, if sufficient to indent or crush it will not necessarily bend the mouth portion even if the force were great enough to bend the cover, since in order so to bend it the tube about it would also have to bend, and its tendency to do so is resisted by the outward pull which then the clips would be caused to exert against the cover at its flange. In fact, I have caused a heavy load to be driven over my improved mailing-tube between its ends and while containing a bottle of liquid, and the only effect of crushing the tube was to break the bottle; but none of the liquid contents escaped from the tube.

What I claim as new, and desire to secure by Letters Patent, is—

1. A mailing-tube comprising a tubular body having a permanently-fastened cover at one end and an internal shoulder and flexible metal clips at its opposite end, in combination with a washer seating against said shoulder and a flanged cover seating in said washer against the shoulder in position to be engaged

at its flange by said clips, substantially as and for the purpose set forth.

2. A mailing-tube comprising a waterproof tubular body having a permanently-fastened cover at one end and an internal shoulder and flexible metal clips at its opposite end, in combination with a washer seating against said shoulder and a circular outwardly-convex cover B having the circumferential flange *i* and seating against said washer in position to be engaged at its flange by said clips, substantially as and for the purpose set forth.

3. A mailing-tube comprising a waterproof tubular body formed of the external and internal tube-sections A' and A² fastened together and forming the shoulder *r* at one end, said tube being permanently closed at its opposite end, and clips C having openings *o* at which they are keyed between said tube-sections to extend beyond said shoulder, in combination with a flanged cover B seated against said shoulder in position to be engaged by said clips, substantially as and for the purpose set forth.

4. A mailing-tube comprising, in combination, a waterproof tubular body A formed of the external and internal tube-sections A' and A² fastened together and forming the internal shoulders *r* and *r'* at its opposite ends, a head *p* permanently seated against the shoulder *r'* and having a cover *m* extending over it, clips C having openings *o* at which they are keyed between said sections at the end of the tube adjacent to the shoulder *r* to extend beyond it, a washer *h* seated against the shoulder *r* and a cover B provided with a circumferential flange *i* and seating against said washer in position to be engaged by said clips, substantially as and for the purpose set forth.

GEORGE P. MCINTYRE.

In presence of—

J. W. DYRENFORTH,
D. W. LEE.
